J. H. McILVAINE

LIQUID FUEL BURNING APPARATUS

Filed Aug. 23, 1926

By John H. McIlvaine
Wilson & McCanna
Atty.

UNITED STATES PATENT OFFICE.

JOHN H. MCILVAINE, OF LAKE FOREST, ILLINOIS.

LIQUID-FUEL-BURNING APPARATUS.

Application filed August 23, 1926. Serial No. 130,836.

This invention relates to liquid fuel burning apparatus, such as oil burners, and is principally concerned with the provision of an oil burner of the pressure or force feed type which is convertible to gravity feed operation in an emergency, such for example as might arise due to a failure of the pump or the electric current supply for the driving motor therefor.

10 The principal object is to provide in the fuel delivery line, which is normally fed with fuel under a certain pressure by a pump operated electrically or otherwise, an auxiliary feed connection or by-pass to the delivery line so arranged with respect to the source of fuel supply for the pump that fuel is fed therethrough by gravity. This bypass connection is in turn restricted so as to furnish only a fraction of the normal oil delivery such as will keep the furnace operating satisfactorily by a natural chimney draft and without undue smoking temporarily until the normal force feed and air blower draft is resumed.

15 According to the present invention a two-way connection is provided at the outlet side of the pump with the fuel delivery line and a stand pipe in which a certain level of fuel is maintained when the pump is in normal operation, the one way in said connection serving as the main fuel supply duct and establishing communication between the fuel delivery line and the outlet side of the pump at a point above the level of fuel in the fuel reservoir from which the pump is supplied with fuel. The other way in said connection is in the nature of a by-pass and establishes communication between the fuel delivery line and the outlet side of the pump

20 at a point below the level of the fuel in the fuel reservoir whereby fuel is fed therethrough by gravity from said reservoir, the by-pass being restricted so that a smaller amount of fuel will be fed therethrough than is otherwise fed through the main fuel supply duct. As will presently appear, the two-way connection is provided in a single cast fitting of a simple and economical construction.

25 The invention is illustrated in the accompanying drawing wherein—

Fig. 1 is a side elevation of an oil burning apparatus embodying my invention shown in connection with a heater or furnace such as is used in homes; and

Fig. 2 is an enlarged sectional detail of the two-way connection by virtue of which the novel manner of operation herein described is secured.

For the purposes of illustrating the present invention I have selected the type of oil burning apparatus disclosed in my copending application, Serial No. 45,448, filed July 23, 1925, but it will be understood that the invention is in no wise limited in its application to this or any other specific form of burner. Briefly stated the apparatus comprises a storage tank 3 supplied with oil from any suitable source such for example as a storage tank. The oil is fed from the tank 3 through a shut-off valve 4 and strainer 5 through a pipe 6 into a float chamber 7. The latter, as described in my copending application, Serial No. 130,835, filed August 23, 1926, is equipped with a lever 8 for depressing the valve stem 9 thereof to shut off the flow of oil to the burner in case of a failure of the flame or in case of excess leakage or some similar eventuality. The oil is delivered from the float chamber 7 through a pipe 10 to a centrifugal pump 11. The latter has a rotary impeller in the casing thereof as described in the application first referred to. This permits passage of oil through the pump when it is out of action, as will appear hereinafter. The float chamber 7 is at a certain elevation with respect to the pump to supply fuel by gravity to the latter. At this point it may be remarked that the oil in the float chamber 7 is maintained at approximately the level of the line *a*—*b*. The pump 11 is driven through a suitable resilient drive connection by a constant speed electric motor 12. The pump and motor are both mounted on a frame 13 in the manner shown. The pump, as described in my copending application first above referred to, has the outlet 14 communicating with a fuel delivery pipe or line 15 and also a stand pipe 16. The revolving of the pump impeller raises the oil above the level of the float chamber to a certain level in the stand pipe 16 which level is maintained substantially constant in the normal operation of the apparatus so that a constant feed of fuel through the line 15 to the furnace is assured. The motor 12 also serves to drive an air blower fan 17 communicating through the delivery pipe 18 with the fire-pot 19 in the furnace 20. The oil delivery line is extended

inside the air delivery pipe, as indicated in dotted lines, to discharge into the fire-pot 19. The blower 17 is arranged to be regulated to proportion the feeding of air to 5 the feeding of oil, as described in my co-pending application. A control valve 21 serves to regulate the rate of flow of fuel through the delivery line. The details thus far generally described form no part of the 10 present invention except insofar as they contribute to the novel combination herein claimed.

claimed.

It will be noted that the outlet 14 has a pipe connection 22 with a fitting 23 of a segmental or generally triangular form. The latter is preferably cast in one piece to provide cored passages or ducts 24, 25 and 26 whereby to provide a two-way connection establishing communication between the pipe 22, and hence the outlet 14 of the pump 11, and the fuel delivery line 15 either through the duct 25 or 26 or both. The duct 25 serves as the main fuel supply duct and communicates with the outlet side of the pump 20 through the passage 24 at the port 27 which, it will be noted in Fig. 1, is at a level above the line $a-b$, in other words, above the level of the fuel in the float chamber 7. In the course of the normal operation of the 25 apparatus when fuel is maintained at a certain level in the stand pipe 16, it will be obvious that fuel will be delivered through the duct 25 to the fuel delivery line 15 at the pressure indicated by the level in the stand 30 pipe 16. The duct 26 on the other hand is in the nature of a by-pass and establishes communication between the fuel delivery line 15 and the outlet side of the pump at the port 28 which is below the level of the line 35 $a-b$, as shown in Fig. 1. That is, the duct 26 will normally be fed with fuel from the float chamber 7 by gravity under a head represented by the difference in elevation 40 of the line $a-b$ and the port 28. The port 45 28, or the duct 26 for that matter, may be provided of a restricted size so that a smaller amount of fuel will be fed therethrough than is normally fed through the duct 25. For practical purposes it is contemplated 50 that about one-third the full load oil delivery will be permitted to pass through the by-pass duct 26. For the purpose of regulating the restriction of the port 28, a needle valve 29 threading in the fitting 23 is provided as shown in Fig. 2. A lock nut 30 and packing washer 31 are provided for the 55 valve 29 for obvious reasons.

In operation it will, therefore, appear that so long as the pump 11 is operated at its normal speed by the motor 12, a certain level of fuel will be maintained in the stand pipe 16 and that fuel will consequently be fed through the main fuel supply duct 25 into the fuel delivery line 15 and from thence to the fire-pot 19, as determined by the setting

of the valve 21. However, when the pump either fails, or is stopped because of a failure of the electric current supply for the motor 12, the oil level in the stand pipe 16 drops down to and below the port 27 to the level of the line $a-b$, thus discontinuing the feeding of oil through the main fuel supply duct 25. In the case of an oil burning apparatus of the ordinary type the flame in the fire-pot 19 would consequently be extinguished. However, according to the present invention a small flow of oil is permitted through the by-pass 26 to keep a small flame burning in the fire-pot 19 while the motor or the pump is temporarily out of operation. The by-pass valve 29 is adjusted, or the by-pass duct is provided of such a size, that about one-third of the normal full load oil delivery is fed to the burner. It has been found that the burner will, in an emergency, operate satisfactorily with this amount of fuel with natural chimney draft without undue smoking during a temporary shut down of a few hours. Then as soon as the pump is restored to operation, as for example by the electric current supply being restored, the burner will pick up from its small gravity flame to its normal flame. In this way the fire-pot is never permitted to cool off so as to require pre-heating. In fact, this manner of automatic operation avoids the necessity of looking after the burner or attending to it in any way when the shut down is due simply to a temporary failure of the electric current supply. Where the failure of the apparatus is due to some other cause it will, of course, be obvious from the description that the burner will be kept operating until the fault is remedied.

It is believed that the foregoing description conveys a clear understanding of the invention and of its purposes and advantages and, while I have illustrated but a single working embodiment, it should be understood that various changes might be made in the construction or arrangement of parts as may be required in different applications and for furnaces and heaters of different types without, however, departing from the spirit and scope of the invention as expressed in the appended claims.

I claim:

1. In a liquid fuel burning apparatus a pump, a fuel reservoir at a certain elevation with respect thereto for delivering fuel to said pump by gravity, a fuel delivery line to be supplied with fuel from said pump normally under a certain pressure and extending to a furnace to be supplied with fuel, a stand pipe communicating with the outlet side of said pump and arranged to have a certain level of fuel maintained therein in the normal operation of said pump, and a two-way connection between the outlet side of said pump and said fuel delivery line and

- stand pipe, the one way in said connection serving as a main fuel supply duct and establishing communication between the outlet side of said pump and said fuel delivery line at a point above the level of the fuel in said fuel reservoir, and the other way in said connection serving as a by-pass establishing communication between the outlet side of said pump and the fuel delivery line below the level of fuel in said fuel reservoir whereby to be fed with fuel by gravity therefrom, but being restricted so that the rate of flow of fuel therethrough is slower than is otherwise the case through the other connection.
- 5 2. In a liquid fuel burning apparatus as set forth in claim 1, the provision of a regulating valve for adjusting the restriction of said by-pass connection.
3. In an apparatus of the character described, the combination of a pump having an impeller in the casing thereof which permits the passage of fuel through the casing when the pump is inactive, a fuel supply line extending to the pump furnishing fuel 20 to the inlet thereof under a given low head, and a single fuel delivery line leading from the pump outlet to a burner supplied thereby, said line having a normal feed opening at a certain elevation reached by fuel during 25 the operation of the pump and having at a lower level, low enough to be reached by fuel fed under the low head from the supply line through the pump casing, a restricted by-pass opening which, when the pump is 30 inactive, is arranged to conduct to the burner the fuel seeping through the pump casing.
4. In an apparatus of the character described, the combination of a pump having an impeller in the casing thereof which permits the passage of fuel through the casing when the pump is inactive, a fuel supply line extending to the pump furnishing fuel 35 to the inlet thereof under a given low head, a single fuel delivery line leading from the pump outlet to a burner supplied thereby, and a single fitting connected between said pump and said line, said fitting having a normal feed opening at a certain elevation reached by fuel during the operation of the 40 pump and having at a lower level, low enough to be reached by fuel fed under the low head from the supply line through the pump casing, a restricted by-pass opening which, when the pump is 45 inactive, is arranged to conduct to the burner the fuel seeping through the pump casing.
5. In a liquid fuel burning apparatus, the combination with a single fuel delivery line, a pump for feeding fuel thereto, and means supplying fuel to the pump, of a two-way connection between the line on the one hand and the pump and fuel supply means on the other hand, said connection comprising a body having a fuel inlet opening 50 communicating with the pump and supply 55 means and a fuel outlet opening communicating with the line, and a pair of passages therein affording communication between the inlet opening and the outlet opening, one of said passages being arranged for communication with the inlet opening at a certain level and permitting a restricted flow of fuel therethrough to the outlet opening, and the other passage being arranged for communication with the inlet opening at a higher elevation and permitting a relatively unrestricted flow of fuel therethrough to the outlet opening.
6. An apparatus as set forth in claim 5 wherein the two-way connection has an adjustable restriction valve for controlling the flow of fuel through the first mentioned passage.
7. In a liquid fuel burning apparatus, the combination with a single fuel delivery line, a pump for feeding fuel thereto, and means supplying fuel to the pump, of a two-way connection between the line on the one hand and the pump and fuel supply means on the other hand, said connection comprising a cast hollow body generally triangular in form, the passage in the base permitting only a restricted flow of fuel therethrough, and the passages in the two sides permitting a relatively unrestricted flow of fuel therethrough, an outlet opening connected to the aforesaid line and communicating with the one end of the base passage and also with one of the side passages, an inlet opening 80 connected to the pump and fuel supply means and communicating with the second side passage so as to be in communication with the intake end of the base passage and the intake end of the first side passage, the body being so disposed in use that the intake end 85 of the base passage is at a lower elevation than the intake end of the first side passage.
8. An apparatus as set forth in claim 7 wherein the two-way connection has a needle valve threaded into the body at one end of the base to control the flow of fuel through the base passage.
9. In an apparatus as set forth in claim 7 wherein the two-way connection has the inlet opening at the junction of the base and one side of the body, the provision of an opening at the other end of said side, and a stand pipe extending from said opening.
10. In a liquid fuel burning apparatus, the combination of a main fuel supply tank, a float chamber supplied therefrom and arranged to maintain a predetermined constant level therein so long as there is fuel in the main supply tank, a pump supplied with fuel from the float chamber, a fuel delivery line supplied with fuel from the pump, and a two-way fitting between said pump and said line having a restricted low level gravity feed passage below the level of fuel maintained in said float chamber,

and a high level force feed passage above the level of fuel maintained in said float chamber.

11. An apparatus as set forth in claim 10 including a standpipe connected to said fitting and extending above the level of the last mentioned passage.

12. An apparatus as set forth in claim 10 including a valve for varying the restriction of the gravity feed passage. 10

In witness of the foregoing I affix my signature.

JOHN H. McILVAINE.
